US0D1106748S

(12) **United States Design Patent** (10) Patent No.: **US D1,106,748 S**
(45) Date of Patent: ** Dec. 23, 2025

(54) **HUB COVER FOR A STAND MIXER**

(71) Applicant: **WHIRLPOOL CORPORATION**,
Benton Harbor, MI (US)

(72) Inventors: **Daniele Adamo Andreos**, Varese (IT);
Amy Sarah Beisiegel, Berrien Springs,
MI (US); **Aaron McNabb Evans**, St.
Joseph, MI (US); **Lena M. Jacobs**, St.
Joseph, MI (US); **Jessica R.
McConnell**, St. Joseph, MI (US); **John
W. McConnell**, St. Joseph, MI (US);
Brandon Tyler Mock, St. Joseph, MI
(US); **John Jay Myers**, Saugatuck, MI
(US); **Ryan James Rutter**, St. Joseph,
MI (US); **Brittni Morgan Pertjjs**, St.
Joseph, MI (US)

(73) Assignee: **WHIRLPOOL CORPORATION**,
Benton Harbor, MI (US)

(**) Term: **15 Years**

(21) Appl. No.: **29/984,267**

(22) Filed: **Jan. 14, 2025**

Related U.S. Application Data

(63) Continuation of application No. 29/857,667, filed on
Oct. 25, 2022, now Pat. No. Des. 1,063,505.

(57) **CLAIM**

The ornamental design for a hub cover for a stand mixer as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a hub cover for a stand mixer according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a front perspective view thereof in place on an unclaimed stand mixer.

The portions of the article shown in broken line form no part of the claimed design.

The stand mixer shown in broken line in FIG. 8 is environmental only and forms no portion of the claimed design.
